UNITED STATES PATENT OFFICE

DAVID E. HUNTER, OF MUSKEGON, MICHIGAN, ASSIGNOR TO SHAW-WALKER COMPANY, OF MUSKEGON, MICHIGAN, A CORPORATION OF MICHIGAN

FURNITURE TOP CONSTRUCTION

Application filed July 20, 1929. Serial No. 379,679.

This invention relates to improvements in furniture top construction, and more particularly to an improved construction for metal furniture, such as desks, tables, and the like.

The object of the invention is to provide a novel and practical construction for the tops of desks, involving the use of a sheet metal core flanged at its edges to provide 10 projecting edges of substantial thickness, and covering the top and sides of the core with a pliable material, such as linoleum, including the anchorage of its edges, and the application of rounded caps at the corners 15 of the top.

A further object of the invention is to improve upon the construction disclosed in Letters Patent No. 1,542,138 granted to me on June 16, 1925, and a variation of the 20 structure disclosed in my copending application filed July 20, 1929, Serial No. 379,678.

A preferred embodiment of my invention is illustrated in the accompanying drawings, in which

25 Figure 1 is a perspective view of one corner section of a desk embodying my improved features of top construction.

Figure 2 is a view in side elevation of the corner section of the improved top.

30 Figure 3 is a view in vertical section taken diagonally through one corner, as on line 3—3 of Figure 1.

Figure 4 is a view in horizontal section taken on line 4—4 of Figure 3.

35 Figure 5 is a view in vertical section taken diagonally through one corner, as on line 5—5 of Figure 2.

Figure 6 is a perspective view of one of the gusset plates used at each corner.

40 The top A herein shown is designed especially for a metal desk, and as such rests upon and is fastened to a pedestal or base B. The top comprises in general a sheet metal core 1, over which is applied a layer 45 2 of pliable covering material, such as linoleum. The core is shaped or formed to provide the top with projecting or overhanging edges of substantial thickness, namely, by bending its margins downwardly at right 50 angles in the form of depending flanges 1a

and inwardly again at right angles to form reentrant flanges 1b, the bend at the junction of the vertical flanges and top section being rounded on a 90° arc of substantial radius to provide a smooth curved profile about the 55 upper edge of the top, while the junction of the vertical and reentrant flanges is a relatively sharp right bend.

In preparing the core plate, rectangular sections are cut from each corner of the 60 blank, and symmetrically with respect to diagonal lines so that after the marginal flanges are shaped, an opening is formed at each corner of the core, the edges of which are vertical and extend inwardly at right 65 angles to each other from opposite sides of the corner diagonal and include the rounded top corner edge of the core, but not the corner sections of the bottom of reentrant flanges 1b which meet in a mitre joint, that 70 is, in substantially abutting relation along the diagonal. The shape of the corner openings may also be described as conforming generally to the shape of the corner caps which presently will be described.

75 In applying the layer 2 of covering material the same is first cut and trimmed to cover the entire surface of the core, being carried over and around the sides thereof, so that the edges of the covering material 80 terminate along the lower edges of the vertical edge faces of the core, although portions are trimmed away at the corners to provide 85 openings conforming to the corner openings in the core. A suitable cement or adhesive is used in applying the covering material to the core, although additional means are used for binding the edges thereof around the bottom of the core, as will be presently 90 described.

95 The corner caps 4 are metal shells which are applied to the corners after the covering material has been laid over the core, and are mounted in such a manner as to give the appearance of being inlaid in the covering layer, these surfaces being flush. The caps are preferably pressed or cast in brass or bronze, and in vertical section conform 100 exactly with that of the covered core, namely, with a rounded top edge portion and a

straight vertical portion. In transverse or horizontal section the caps are rounded in 90° arcs, thus providing the desk with the round corners desired.

5 To form an anchorage for the corner caps as well as a corner reinforcement for the top, gusset plates 5 are inserted within the interior corner spaces of the core and spot-welded in place. These gusset plates are 10 stamped from sheet metal, and consist of two parallel flat Y-shaped legs 5a, 5a joined at their apexes by a transverse web 5b, having a hole 5c drilled at its center. Along the opposite sides of the web 5b are a pair 15 of ears 5d, 5d bent at angles of 45° to the web and 90° to the outer edges of the Y-shaped legs 5a. These gusset plates are inserted so that the legs 5a lie flat against the top and bottom of the corner spaces and 20 are spot-welded to metal surfaces of the core above and the bottom flanges 1b below, as at 6. The central web thus is positioned vertically and diagonally across the corner with 25 the ears 5d abutting at their forward edges against the inner surface of the core on either side of the corner opening, thus providing a reinforcement to prevent distortion 30 of the core at the corners.

The corner caps are provided with anchoring screws 7 which are soldered or brazed to the inner faces thereof and project diagonally inward so that they can be inserted through the holes in the central web 5b of the gusset plate. A nut 8 applied to the 35 end of the screw and tightened, draws the corner cap tightly to its seat, which is formed by rabbeting the edges of the covering layer so that the surface of the cap will be flush.

40 As a further detail in the formation of the corner caps, it will be noted that the lower edges thereof are offset outwardly to form a squared bead 4a and that the lower edge of the head is extended inwardly to form a 45 short lip 4b which has substantial abutting contact with the rounded edges of the bottom core flange 1b, where it is cut back a short distance in the formation of the corner opening.

50 To complete the structure, narrow flanged rails or strips 9 are applied along the underside of the projecting edges of the top and fastened in place by means of short bolts 10 passing through the rails and the bottom 55 flanges 1b of the core at suitable intervals.

The edge flanges 9a and 9b of the rails project upwardly and embrace the edge of the covering material on the outside and the edge of the core flange on the inside. At 60 the corners the strips abut endwise against the corner caps, with the outer flanges flush with the bead of the caps.

These rails serve the double purpose of 65 holding the edges of the flexible covering material against disengagement from the

core and as a guard rail to decrease the dangers of damage to the edges of the top by direct impact.

I claim as my invention:

1. A top for furniture comprising a core 70 of sheet metal bent to form projecting marginal portions of substantial thickness having a rounded top edge and flat side faces, a layer of pliable covering material applied over said core and extending around the 75 edges thereof to cover the side faces thereof, said core and covering layer having sections removed at the corners thereof, rounded corner caps mounted at each corner and conforming in vertical section substantially to 80 that of the edge of said core and covering layer, and rails applied to the under side of the marginal portion of said core and having an upturned flange adapted to overlap 85 the edges of said covering material, said caps having a bead about their lower edges abutting the ends of the flange of said rails.

2. A top for furniture comprising a core 90 of sheet metal bent to form projecting marginal portions of substantial thickness having a rounded top edge and flat side faces, a layer of pliable covering material applied over said core and extending around the 95 edges thereof to cover the side faces thereof, said core and covering layer having sections removed at the corners thereof, rounded corner caps mounted at each corner and conforming in vertical section substantially to 100 that of the edge of said core and covering layer, gusset plates secured internally at the corners of the core, fastening members connecting said corner caps with said gusset plates, metal rails bolted to the under side of the marginal portion of said core and having an upturned flange adapted to overlap 105 the edges of said covering material, said caps having a bead about their lower edges abutting the ends of the flange of said rails.

3. A top for furniture comprising a sheet metal core having its marginal portions bent 110 at right angles to provide vertical side faces and an inwardly extending bottom flange, a layer of pliable covering material applied over said core and carried around the edges thereof to cover the side faces with portions 115 cut away at the corners, corner caps mounted at each corner flush with said covering material, and flanged metal strips applied to the underside of said bottom flange, the outer flanges thereof embracing the lower edges 120 of the covering material and having flush abutting contact with the end edges of said corner caps.

Signed at Muskegon, Mich., this 16th day of July, 1929.

DAVID E. HUNTER.
